UNITED STATES PATENT OFFICE

HAROLD B. DONLEY AND HOWARD BALZER, OF COLUMBUS, OHIO, ASSIGNEES TO THE COLUMBUS AUTO BRASS COMPANY, OF COLUMBUS, OHIO, A CORPORATION OF OHIO

OIL MEASURE

Application filed March 30, 1928. Serial No. 266,050.

This invention relates to improvement in oil measures and particularly refers to that class of measures employed by garages, automobile service stations and the like for the purpose of measuring, selling and dispensing internal combustion engine lubricants.

It is the primary object of this invention to provide a measure of the type embodying improved features of construction having a novel form of control valve for regulating the outflow of the lubricant from the measuring chamber of the device into the outlet conduit.

A further object resides in mounting the valve and its operating mechanism on the bottom wall of the measure, for the purpose of obtaining economy and facility in manufacture and to procure improved operation on the part of the valve mechanism itself.

With these and other objects in view, as will appear as the description proceeds, the invention consists in the novel features of construction, combinations of elements and arrangements of parts hereinafter to be fully described and pointed out in the appended claim.

In the accompanying drawing:

Figure 1 is a vertical sectional view taken through an oil measure constructed in accordance with the features of the present invention,

Figure 2 is a horizontal sectional view taken on the plane indicated by the line 2-2 of Figure 1,

Figure 3 is a vertical sectional view taken on the line 3-3 of Figure 1,

Figure 4 is a detail horizontal sectional view on the line 4-4 of Figure 3,

Figure 5 is a detail enlarged vertical sectional view of the valve mechanism.

Referring more particularly to the drawing numeral 1 designates the improved oil measure comprising the present invention. The measure is formed to comprise a sheet metal casing or body 2 generally of frustoconical formation. Externally the body 2 is provided with a suitable gripping handle 3 by means of which the measure may be

manipulated. Within the body 2 the measure is provided with a substantially horizontal extending bottom wall 4, above which is disposed the oil receiving and measuring chamber 5 of the device. Any suitable method may be employed for holding the wall 4 in its operative position. In this instance the peripheral edge of the wall 4 is flanged to snugly engage with the conical inner wall of the body 2. The flange may be welded to retain the wall 4 in a secured position.

The wall 4 which forms the bottom of the measuring chamber 5, is bulged downwardly to produce a sump 6, in the lowermost portion of which is formed an opening for the discharge of the lubricant. Fitted within the opening is an elbow member 7 which is disposed below the bottom wall 4 and is connected with a tubular and flexible metallic conduit 8. The latter carries at its outer end a fixed nozzle 9 which is normally engaged with a stationary hook 10, stationarily carried by the body 2 as shown in Figure 1.

Controlling the outlet of the opening in the bottom of wall 4 is a valve mechanism which in this instance comprises a substantially U shaped bracket 11. Fixed to the bottom wall 4 the spaced legs of the bracket are provided with registering apertures for the reception of a transversely extending cotter pin 12. The latter pivotally carries a substantially L shaped arm 13, which has its outer portion provided with an offset lug or foot 14. Cooperative with the lug or foot and carried thereby is a valve disk assembly consisting of flat horizontally extending washers between which is positioned a valve disk 15. The washers and valve disks are provided with registering openings, axially positioned to register with a similar opening formed in the lug 14. This opening is adapted to receive a rivet or the like 16 so that the valve disk assembly will be unitarily related with the arm 13 and the disk assembly will swing in unison with the arm 13 above the horizontal axis of the cotter pin 12.

Surrounding the cotter pin 12 and posi-

tioned within the bracket 11 are the central convolutions of a wire spring 17. One end of the spring bears on the disk assembly 15 to hold the latter in a seated position normally closing the outlet in the bottom 4, while the other end of said spring rests upon and engages with the inner wall of the body 2 in order to permit said spring to exert proper action in maintaining the valve disk in its said position.

10 To elevate the disk assembly so as to permit of the outflow of the lubricant from the measuring chamber 5, there is mounted on the wall 4, in spaced relation from the bracket 11, a second bracket 18. The latter 15 bracket carries a link 19, one end of which is pivotally connected as at 20 to the bracket 18 and its other end pivotally connected as at 21 to the intermediate portion of a bar 22, the link 19 serving as a floating pivot for 20 said bar. One end of the bar is pivotally connected as at 23 to the arm 13, while the other end of said bar is positioned within 25 the bifurcated lower end of an operating stem 24, a cotter pin 25 passing through the lower end of the stem and the bar 22 pivotally uniting these elements.

30 The stem 24 projects angularly and upwardly and is loosely receivable within an opening 26 formed in a stationary lip 27 carried by the upper and inner portion of the body 2. It will be observed that the stem is formed with a groove or recess 28 which provides a shoulder. While only one 35 groove is shown it will be understood that the stem may be formed with a plurality of grooves or recesses at spaced intervals. The restricted portion of the stem defined by said groove or recess is receivable within a restricted slot 29 provided in connection with 40 the opening 26 in the lip 27. By this construction the valve assembly may be locked in an open position or may be conveniently released from its locked position for actuation by the upper thumb engaging end 30 of 45 the stem 24. This thumb engaging portion is situated adjacent to the handle 3 so that the operator may with practically one operation open the valve assembly to permit of 50 the outflow of the lubricant or by locking the stem through the means described the valve assembly may be retained in its open position with regular continuous pressure on the part of the operator to maintain the 55 assembly in such position.

60 In view of the foregoing it will be seen that the present invention provides an oil measure particularly adapted for use in garages and other automobile service stations. The outstanding feature of this measure resides in the formation and mounting of the valve assembly in connection with the bottom of the measuring chamber. It will be observed that the entire valve assembly including the operating mechanism may be

65 mounted on the bottom 4 prior to the time when the bottom is inserted into the body of the measure. This permits of very considerable manufacturing convenience and economy and moreover the construction provides a secure and permanent base for the 70 valve mechanism, enabling the relationship between the various parts thereof to be fixed and maintained so that said valve mechanism will at all times operate freely and 75 positively. This is in contrast with prior constructions wherein the valve mechanism is applied and positioned following the securing of the bottom within the measure.

What is claimed is:

80 An oil measure device comprising a body, a wall secured within said body and constituting the bottom of an oil measuring chamber said body being provided with a discharge opening, a conduit leading from said discharge opening, a valve disk for controlling fluid flow through said opening, a bracket mounted on said bottom, an arm 85 pivotally secured to said bracket and having the outer portion thereof secured to said disk, spring means carried by said bracket and operating on said disk to normally maintain the same in a closed position, a bar pivotally connected at one end of said arm, a floating link having the upper portion connected with an intermediate part of said bar, the lower end of said link being pivotally 90 connected with the bottom wall, and an operating stem connected with the outer end of said bar and extending above said body.

95 In testimony whereof we affix our signatures.

100 HAROLD B. DONLEY.
HOWARD BALZER.
